(57) **CLAIM**

The ornamental design of a food jar, as shown and described.

DESCRIPTION

FIG. 1 is a perspective view from above and to the right of the food jar;

FIG. 2 is a perspective view from below and to the left of the food jar;

FIG. 3 is a front elevation view of the food jar;

FIG. 4 is a left side view of the food jar, with the right side view being a mirror image of FIG. 3;

FIG. 5 is a back elevation view of the food jar;

FIG. 6 is a top plan view of the food jar; and,

FIG. 7 is a bottom view of the food jar design.

It is to be understood that the broken lines are for illustrative purposes only and form no part of the claimed design.
